LOUIS EDOUARD RIVOT, OF PARIS, FRANCE, ASSIGNOR TO JACQUES GAILLARDON, OF SAN FRANCISCO, CALIFORNIA.

Letters Patent No. 73,840, dated January 28, 1868.

IMPROVEMENT IN TREATING ORES WITH SUPERHEATED STEAM.

The Schedule referred to in these Letters Patent and making part of the same.

TO WHOM IT MAY CONCERN:

Be it known that I, LOUIS EDOUARD RIVOT, of Paris, in the Empire of France, have invented certain new and useful Improvements in the Method of and Means for Treating Auriferous and Argentiferous Ores; and I hereby declare the following to be a full, clear, and exact description of the same, reference being had to the accompanying drawings.

In Letters Patent of the United States, granted me on May 31, 1864, No. 42,997, I have detailed the operations of which the process of treating the argentiferous and auriferous ores is composed. They may be said to consist of the roasting, by means of superheated steam, of pulverized ore, either alone or mixed with a suitable proportion of pyrites, and of the amalgamation of the roasted ore without the addition of reagents. I proposed for the roasting a reverberatory furnace, heated with wood or coal.

The object of the present invention is to produce a furnace which may take the place of the reverberating furnace, in the operation of roasting the ore by means of superheated steam.

The ore is placed in a horizontal sheet or cast-iron cylinder of large dimensions, and superheated steam is admitted at one end of the cylinder, while the excess of steam, and the products of the action of the steam upon the ore, issue from the other end of the cylinder, and pass into the chimney. This cylinder revolves slowly, so as to continually expose new surfaces to the action of the steam, and thus dispense with the working and rabbelling by the operator. The cylinder, which is of a special form, is arranged in a furnace heated with wood or coal. The flames from the fire-chamber are first made to superheat the steam, and then to raise the cylinder to a proper temperature by means of steam, and then finally pass into the chimney, which receives also the products which issue from the cylinder. Both the cylinder and the furnace are represented in the drawing hereunto annexed, in which—

Figure 1 represents a horizontal section of the furnace, on line 3 4 5 6, fig. 2. The cylinder is shown in plane view, in order that its position in the furnace may be more readily understood.

Figure 2 represents a vertical section of the furnace, on line 1 2, fig. 1.

Figure 3 represents a transverse section of the furnace, on line 7 8, fig. 1.

Figure 4 is an end view of the furnace.

The dimensions shown in the figures are those applicable to a cylinder, in which a charge of ore of about five hundred kilogrammes is worked. It will be easy to increase or diminish the dimensions, according to circumstances.

The fuel, whether it be wood or coal, lignite turf, &c., is charged, through the door P, into the fire-chamber f. The annexed drawing shows an arrangement of door and fire-chamber suitable for burning wood. It will be easy to modify the arrangement, if mineral fuel be used. The flames are divided by the wall e, which extends upward to the arch of the furnace. They then pass under the cylinder C, and rise on the opposite side, in order to enter the four flues a, which convey them to the chimney B.

Steam from the generator passes through the pipe v, and thence through the second pipe, v', and out of the furnace through the third pipe, v''. The last is bent outside of the furnace, and unites in the sleeve with the pipe y, which is attached to the cylinder. In passing through the three pipes, which are entirely enveloped by the flames, the steam acquires a high temperature. It would be easy to further superheat it, by placing two pipes against the vertical wall of the fire-chamber, on the fire-bridge side. Whatever may be the number of pipes heated by the flames, it will be well to place the elbows outside of the masonry, as indicated in fig. 1 of the drawings.

In each end of the furnace a recess is formed in the masonry, parallel with the cylinder, and the cylinder is held underneath by means of a solid cast-iron bracket or girder, as shown in the drawings. The two ends of the furnace correspond with the two ends of the cylinder, and are made of cast-iron plates, held in place by means of four solid cast-iron braces. On top the furnace is provided with a sheet-iron plate, arched and strengthened by means of braces. The cylinder is made either of cast or boiler-iron. In the drawings, a cast-iron cylinder is shown. It is cast in two pieces, which are joined together by means of an exterior ring, m.

In figs. 2 and 3, it will be seen that the cylinder is furnished on the inside with eight projecting ribs,

extending the whole length of the cylinder, the object being to cause the ore to change position at each rotation of the cylinder, and they are thus intended to produce, in connection with the rotary movement, the effect of rabbling of the ore in a reverberatory furnace. There may be similar ribs on the outside, which are cut away at the points where the hoops $m m' m''$ pass around the cylinder, their object being to hold the hoops in place. These hoops are flanged, so as to admit rollers $g g' g''$ between them. The rollers and their journals are of wrought iron, and their bearings are of cast iron.

The two end plates of the cylinder are secured by bolts. One of these plates, E, is connected with the pipe through which the superheated steam is admitted, and is provided with two doors for charging and discharging. The other end plate, E', is cast with the exit-pipe, which opens into the chimney. A door is arranged in this pipe, to allow the workman to observe the nature of the gas which escapes under the action of the steam. The chimney-wall is pierced with a circular opening, lined with a cast-iron collar of a diameter larger than that of the steam-escape pipe, so that the latter may freely revolve with the cylinder.

Rotary movement is imparted to the cylinder by means of two gear-wheels, R R', placed on the cylinder, but outside of the furnace. They are driven by means of pinions, $r r'$, fast on a shaft above the cylinder, and on the outside of the furnace. The shaft is supported by means of two cast-iron bearings, at the extremities of the furnace, and by a third bearing secured within the masonry of the chimney. Power is transmitted to a pulley on the shaft, in the vicinity of the end E' of the cylinder. The rotation of the cylinder is then effected upon the rollers by the action of the gear-wheels, so that the rotation is necessarily upon the axis of the cylinder. The rotary movement should be very slow, but may be raised with the nature of the ore. As a general thing, the cylinder should make from twenty to thirty revolutions per hour.

For the admission of steam I use a special arrangement. It is necessary that the steam pass from the fixed superheating pipe into the rotating pipe, at the end of the cylinder, without loss. It is also necessary that the outer air should not enter into the latter pipe. To this effect I propose the arrangement shown in section, fig. 3. v'' is the pipe which receives the steam from the superheater. y is the pipe which revolves with the cylinder. The pipe y is enlarged at its extremity, and overlaps the end of the pipe v'' about one centimetre. The end is smooth, and is in frictional contact with the vertical flange o , cast on the pipe v'' . The coupling of these two pipes is enclosed in a cast-iron box, A, which is bolted on one side with the annular flange e , which is also cast on the fixed pipe v'' . At the other end the box is provided with the annular flange B' , whose exterior surface is smoothly polished and slightly conical. This flange is recessed, to allow the passage of the enlarged end of the pipe y , which carries a tight-fitting sleeve, M, whose conical flange corresponds with that designated by the letter B' . When the two pipes are placed in position, the sleeve M is pressed up against the flange B' , and there will then be no escape of superheated steam, nor penetration of the outer air. For greater safety, however, steam is admitted into the box A through the pipe t . The box A is supported by an iron frame, so as to allow the operator to use the tools requisite to charge and empty the cylinder.

Each operation is divided into three stages—the charging, the steaming, and the discharging.

First stage. The cylinder is stopped in the position shown in fig. 4. The two doors, P P'', are open, and the ore is charged through a hopper not shown in the figure, as there is nothing novel in its arrangement. A movable iron plate conducts the ore from the hopper to the cylinder through the door P', while the operator, by means of a rabble, pushes the ore to the bottom of the cylinder, and equalizes or levels the mass.

Second stage. The cylinder is put in motion by revolving it from left to right, that is to say, in the direction of the flames under the cylinder. Steam is admitted in such quantity as to fill slowly the cylinder. The fire is then augmented, so as to bring the cylinder to a dull red. The action of the steam then commences, which can be observed through the orifice O in the chimney. The time required to complete the roasting varies with the nature of the ore. The completion of the roasting may be ascertained, first, when, on looking through the opening O in the chimney, no escape of yellow vapor or odor is perceptible; second, when, on introducing through the door I of the escape-pipe a piece of paper impregnated with a salt of lead, (for instance, acetate of lead,) the paper does not become black.

Third stage. When the ore has been roasted, steam is shut off, the cylinder is stopped in the same position as for the charging, and the two doors P P'' are opened. The operator, by means of a rabble, then shovels out the ore, and drops it on the ground, or into a wheel-barrow, in which it is carried off to some place of deposit.

Having thus described my invention, and the manner in which the same is or may be carried into effect, what I claim, and desire to secure by Letters Patent, is—

The herein-described method of and apparatus for roasting argentiferous and auriferous ores, that is to say, the employment, in connection with superheated steam, of a rotary roasting-cylinder, substantially in the manner shown and specified.

In testimony whereof, I have signed my name to this specification before two subscribing witnesses.

L. E. RIVOT.
